US0D1029801S

(12) **United States Design Patent** (10) **Patent No.:** **US D1,029,801 S**
(45) **Date of Patent:** **** Jun. 4, 2024**

(54) **WIRELESS EARPHONE**

(71) Applicant: **AFH Industries Inc.**, New York, NY (US)

(72) Inventors: **Isaac Saideh**, Brooklyn, NY (US); **Geoffrey Lawrence Eisenhardt**, Olathe, KS (US)

(73) Assignee: **AFH Industries Inc.**, New York, NY (US)

(**) Term: **15 Years**

(21) Appl. No.: **29/834,606**

(22) Filed: **Apr. 13, 2022**

(51) **LOC (14) Cl.** **14-01**

(52) **U.S. Cl.**

USPC **D14/223**

(58) **Field of Classification Search**

USPC ..... D14/205, 207, 217, 221, 223, 225; D24/106, 173, 174; D29/112 CPC . H04R 1/08; H04R 1/10; H04R 1/105; H04R 1/1016; H04R 1/1033; H04R 1/1066; H04R 5/033; H04R 5/0335; H04R 25/00

(57) **CLAIM**

The ornamental design for a wireless earphone, as shown and described.

DESCRIPTION

FIG. 1 is a front perspective view of a wireless earphone showing an embodiment of our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines show environmental subject matter that form no part of the claimed design.

1 Claim, 6 Drawing Sheets
